H. B. WORRELL.
ODORIZING DEVICE.
APPLICATION FILED JUNE 23, 1914.

1,199,033.

Patented Sept. 19, 1916.

UNITED STATES PATENT OFFICE.

HARRY B. WORRELL, OF COLUMBUS, OHIO.

ODORIZING DEVICE.

1,199,033.

Specification of Letters Patent. Patented Sept. 19, 1916.

Application filed June 23, 1914. Serial No. 846,897.

To all whom it may concern:

Be it known that I, HARRY B. WORRELL, a citizen of the United States, residing at Columbus, in the county of Franklin and 5 State of Ohio, have invented certain new and useful Improvements in Odorizing Devices, of which the following is a specification.

My invention relates to odorizing devices 10 of a type for use for impregnating the air of a room with some desired mist or fluid. This mist or fluid may be of a perfumed nature or in the nature of a disinfectant or may be simply water vapor to govern the 15 humidity of the air within the room, these various conditions being to the taste and requirement of the user.

My invention is designed to form an attachment to the ordinary type of electric 20 fan now in use and comprises essentially a receptacle containing the odoriferous compound located in the path of the created draft of air. In this manner, the air is caused to pass through the compound and 25 become impregnated and later circulated about the room.

Another object of my invention resides in providing a wick member for this receptacle, the wick member being partially 30 immersed in the odorizing liquid within the receptacle and projecting to a position directly in the path of the created draft of air.

Other objects of my invention will become 35 more apparent after a further detailed description of the accompanying sheet of drawings, in which similar characters of reference designate corresponding parts, and in which:

40 Figure 1 shows a conventional type of electric fan with my attachment applied thereto, Fig. 2 is a central vertical section taken through the attachment, or on line 2-2 of Fig. 3, Fig. 3 is a section taken on line 3-3 of Fig. 2, Fig. 4 is a top plan view of my attachment with the cover removed, Fig. 5 is a view in perspective of the rear side of my attachment, Fig. 6 is a view in perspective of the front side of my attachment, and Fig. 7 is a view in perspective of 50 a portion of the attaching device.

In Fig. 1, the fan is shown as comprising a pedestal 1, upon which is suitably mounted the fan motor confined within a casing 2. The central shaft of this motor carries 55 the fan wheel shown at 4 and this fan wheel,

as is customary, is shown as being provided with a wire guard member 5.

My attachment takes the form of a casing 6 attached in any desired manner to the fan as a whole in the path of the created draft of air. In the present instance, I have concaved the lower portion of this receptacle as is shown at 7 and provided the inner edges of each of the legs 8 formed with this concaved portion, with ears 9, through which project thumb screws 10. The receptacle is adapted to seat itself upon the upper portion of the motor casing to be partially held in this position by tightening 60 of the thumb bolts 10. The front and rear walls of this receptacle are each provided with suitable openings to permit the free flow of air therethrough. The opening in the front wall is shown as being a great 65 number of small apertures covering a comparatively large area as at 11, while the rear wall is provided with a plurality of considerably larger apertures 12. Located 70 within the receptacle and between the openings 11 and 12 is the major portion 13 of a wick member, the lower portion being provided with tail pieces 14 adapted to enter 75 the legs 8. The receptacle is partially filled with whatever liquid may be desired and 80 this liquid is absorbed by the wick member until it becomes saturated. The subsequent 85 passage of air through the receptacle by means of the openings 11 and 12 will cause 90 a vaporization of a portion of this liquid by 95 its forced passage through the wick and consequently this air will become scented, as is desired. The wick member itself is supported and held in its stretched position by means of the wire frame 15, this frame being 100 shown as being rectangular in shape and having its end wires projecting slightly beyond the edge of the wick. These end wires are adapted to slide up and down within guideways formed by angle pieces 105 16 located on the end walls of the receptacle 6. After the wick has been placed in its position, the casing 6 may be closed along its upper side by means of a lid 17, which lid has its edge portion curled as is shown 110 at 18 to embrace outstanding flange portions 19 on the sides of the casing proper.

It is desirable that the casing 6 should also be given support adjacent its upper portion and to this end I have provided a member 20 adapted to be securely attached to the casing in any desired manner, as is shown

at 21, this member being provided with an outstanding leg 22 suitably fitted at its outer end for the reception of an attaching screw 23. This outstanding leg 22 is adapted to 5 coöperate with a complementary leg 24 of an embracing member formed of sections 25 and 26. The leg 24 is slotted as is shown at 27, within which the screw 23 is adapted to 10 slide to accommodate the various sizes and makes of fans. The outer end of this member has its sections 25 and 26 internally concaved as is shown at 28 to embrace the rim wires forming a portion of the guard member 5. The sections 25 and 26 are 15 formed separate and may be held in their clamped relation by the screw 29. These sections are further formed with a semi-circular cut-out portion 30, so that the attachment will not interfere with the point 20 of connection of one of the cross wires 31 of the guard member 4 with the rear frame wire 32.

When my attachment is applied, the thumb bolts 10 are tightened to securely 25 grip the outer wall of the motor casing, while the upper connection is adjusted to be attached to the rear frame wire 32 of the guard member 5 in a manner so that the receptacle 6 will be held in a substantially 30 vertical position. This receptacle is then partially filled with the desired liquid, whereupon the wick member 13 is placed in its position and definitely held so by means of its wire frame 15 and angle guideways 35 16. The lower portion of this wick is partially immersed in the liquid and consequently the wick will absorb the same until it reaches its saturation point. If the fan is then set in operation, a draft of air will be 40 created and a portion of this air will be forced through the saturated wick because of the openings 11 and 12 in the side wall of the casing. This air will then become impregnated with the liquid and be circulated 45 about the room in which the fan is located. In this way, the room may be scented or filled with a mist for whatever purposes may be desired.

What I claim, is:

50 1. An odorizing attachment for fans comprising a receptacle mounted on said fan in

the path of the created draft of air and having its opposite sides provided with openings in line with said created draft, guideways on the inside ends of said receptacle, 55 a framework slideable in said guideways, and a wick supported on said framework between said openings.

2. An odorizing attachment for fans comprising a receptacle mounted on said fan in 60 the path of the created draft of air and having its opposite sides provided with openings in line with said created draft, guideways on the inside ends of said receptacle, a rectangular wire framework slideable in said 65 guideways, and a flat wick stretched between the upper and lower portions of said framework between said openings.

3. An odorizing attachment for fans comprising a receptacle formed with a concaved 70 bottom to partially embrace the fan, said receptacle being mounted on said fan in the path of the created draft of air and provided with opposed openings in line with said created draft, a wick and its supporting 75 framework mounted within said body and between said openings, and tail wicks carried by said first named wick arranged to extend into the legs formed by said concaved bottom. 80

4. An odorizing attachment for fans provided with a wire guard surrounding the fan blade comprising a receptacle formed to partially embrace the fan body and mounted thereon in the path of the created draft 85 of air, ears on the lower portion of said receptacle, bolts passing through said ears and adapted to engage said body, an adjustable device at the top of said receptacle arranged to engage said wire guard, said receptacle being provided with openings in 90 opposite walls above its normal liquid level for the passage of air and in line with the created draft of air, and a wick within said receptacle located between said openings. 95

In testimony whereof I affix my signature in presence of two witnesses.

HARRY B. WORRELL.
